UNITED STATES PATENT OFFICE.

WILLIAM J. SCOTT, OF ALBANY, NEW YORK, ASSIGNOR TO JACOB C. E. SCOTT, HELEN M. SCOTT, AND MARTHA J. SCOTT, ALL OF SAME PLACE.

COMBINED HAIR-BRUSH AND COMB.

SPECIFICATION forming part of Letters Patent No. 397,614, dated February 12, 1889.

Application filed July 13, 1887. Serial No. 244,145. (No model.)

To all whom it may concern:

Be it known that I, WILLIAM J. SCOTT, of the city and county of Albany, and State of New York, have invented a new and useful 5 Combined Hair-Brush and Comb, of which the following is a specification.

My invention relates to improvements in combined hair-brushes and combs; and the object of my invention is to provide a combined hair-brush and comb wherein the points of the teeth of the latter will be normally held by springs by which it is connected to the brush to project beyond the outer ends of the tufts of bristles, so that the brush and 10 comb will always perform their several functions conjunctively. This object I attain by the construction illustrated in the accompanying drawings, which are herein referred to and form part of this specification, and in 15 which—

Figure 1 is a perspective view of the preferred form of my invention, in which the comb is attached to the brush by means of springs; Fig. 2, a longitudinal section of the 20 same, and Fig. 3 an enlarged and detached plan view of the comb and its attached springs.

As represented in the drawings, A is the hair-brush, which may be made of any preferred form, size, and material; B, the comb, 25 which is placed transversely across the brush A in the bristles of the latter, and preferably a little nearer the handle *a* than the opposite end of the brush, so that the bristles between the comb and handle will prepare the hair 30 for the reception of the comb, and the balance of the brush will complete the straightening and smoothing of the hair. As shown in Figs. 1, 2, and 3, said comb is attached to the springs

C, which are made of spring-wire or other suitable material and secured to the plate D. 40 Said plate is secured to the back-piece *a'* of the brush in such manner that the points of the comb-teeth will normally project beyond the ends of the bristles of the brush, and so that the comb B can have free movement 45 toward the back-piece *a'*. Stops *c* are fixed on the springs C to engage in the perforated plate E, inserted in the back-piece *a'*, for the purpose of preventing the displacement of the comb B by a movement of the brush A in 50 the wrong direction.

The brush is drawn over the hair by means of the handle *a*, and the projecting teeth of the comb B will straighten the entangled hair, which will be smoothed down by the 55 bristles of the brush, which follow after the comb. The springs C will yield to a sufficient degree to permit the bristles of the brush to operate effectively on the hair and do servicable work on the hair when the latter is 60 thin.

I claim as my invention—

A comb combined with a hair-brush in the manner herein described, said comb being fixed amid the bristles of the brush and attached to springs, whereby the points of the comb-teeth will be normally held to project beyond the outer ends of the tufts of bristles and in such manner that the operations of combing and brushing can only be effected 70 conjunctively, as and for the purpose herein specified.

WILLIAM J. SCOTT.
